UNITED STATES PATENT OFFICE.

ROBERT H. BEAUMONT, OF RADNOR, PENNSYLVANIA, ASSIGNOR TO R. H. BEAUMONT COMPANY, OF PHILADELPHIA, PENNSYLVANIA, A CORPORATION OF PENNSYLVANIA.

RELEASE FOR THE AUTOMATIC BRAKES OF WINDING DRUMS.

Application filed February 28, 1927. Serial No. 171,461.

In the operation of winding drums arranged to haul an object in two directions, as a drag scraper bucket back and forth, by means of lines or ropes attached to the object and wound one of them onto one drum and the other of them onto another drum, it is customary to provide automatic brakes operative on the drum which is playing out cable so as to provide tension against which the other drum works, and the purpose of this is to keep the object in a straight path and to avoid whipping of the lines.

The principal objects of the present invention are, first, to permit such drums to be overhauled and rope played out, as in drag scraper work, whenever the total length of lines or ropes out in the storage field has to be changed to accommodate different positions of the scraper bucket; and second, to provide simple, reliable and efficient mechanism operable by hand for releasing the automatic brakes of winding drums.

Other objects of the invention will appear from the following description.

25 The invention comprises the improvements to be presently described and finally claimed.

In the following description reference will be made to the accompanying drawing forming part hereof and in which

30 Figure 1 is an elevational view partly in section illustrating a release for the automatic brakes of winding drums embodying features of the invention.

Fig. 2 is a view drawn to an enlarged scale 35 and illustrating features of the invention, and

Fig. 3 is a top or plan view of Fig. 2 with the brake band and drum omitted.

In the drawing 1 is a brake band which 40 may be fitted with a lining as usual and which is automatically effective in one direction usually playing out direction, as indicated by the arrow in Fig. 1. The mechanism, generally indicated at 2, is a means 45 for accomplishing that result and since it forms no part of the present invention it need not be further described. The brake band is split at 3. 4 and 5 generally indicate a pair of brackets of which one is attached to one end of the band and of which the other is attached to the other end of the band. 6 generally is a lever end pivotally fulcrumed in one of the brackets as by the pins 7, and it is provided with a socket

for the reception of a hand bar. There is a 55 sleeve nut 8 pivoted to the bracket 4. As shown the sleeve nut 8 is mounted in a block 9 pivoted to the bracket 4 by the pins 10. 11 is a rod having a head 12 shown to comprise nuts screwed onto the rod. This rod 60 passes through the sleeve nut and is pivoted to the lever end to one side of its fulcrum 7 as at 13. 14 is a spring interposed between the head 12 of the rod 11, and a shoulder 15, provided on the sleeve nut 8. 65 The brackets 4 and 5 are duplicates and comprise a base 16 curved to conform to the brake band, and a pair of upstanding ears 70 perforated for the reception of pivot pins. The lever end is shown to comprise a pair of plates 17, spaced apart by fastenings 18 and 19, and it is between these fastenings 18 and 19, that a hand bar 20 may be inserted. The plates 17 are shown as providing a toe 75 21 adapted to seat on the base of the bracket 5 when the parts are in normal position, as shown in Fig. 2.

Assuming that the parts are in normal position, the spring 14 operates to put proper tension on the brake band 1 for causing it to cooperate with the face of the drum 22, and the degree of tension of the spring 14 may be adjusted either by shifting the sleeve nut in respect to the block 9, or by shifting the nuts 12. For the sake of further description it will be assumed that the brake band is set by the automatic mechanism 2 sufficiently to produce tension on the outgoing line and that it is desired to play out more line which would have to be done 80 against the tension of the brake which while appropriate for its purpose in connection with power driven machinery might be rather excessive to overcome by hand. Under these circumstances the bar 20 is inserted in the socket of the lower end 6 and turned in counter-clockwise direction in Fig. 2. The result of this is that the pivot pin 13 is turned in the same direction about the fulcrum 7 releasing the tension on the spring 14 and so releasing the brake band and then the line can be readily played out and the drum overhauled. Thereupon the hand bar can be turned counter-clockwise, restoring the tension on the brake band and 85 permitting the toe 21 to seat on the base of the bracket 5.

By way of further description it may be

said that the head 11' of the bar 11 is normally drawn by the spring 14 up against the end (righthand end in Fig. 3) of the sleeve nut 8, thus fixing the length of the 5 brake band and by screwing the sleeve nut 8 into or out of the block 9, the brake band may be lengthened or shortened. When the 10 lever end 6 is turned counter-clockwise the tension on the spring 14 is increased and the end 11' of the rod 11 is pulled away from its stop, i. e. the end of the sleeve nut 8, and it may be remarked that a little space is shown between these parts on the drawing to illustrate this although in practice in the 15 position shown the adjacent ends of 8 and 11' would be in contact.

It will be obvious to those skilled in the art to which the invention relates that modifications may be made in details of construction and arrangement and in matters of mere form without departing from the spirit of the invention which is not limited to such matters or otherwise than the prior art and the appended claims may require.

25 I claim:

1. A release for the automatic brakes of winding drums comprising a split brake band automatically effective in one direction and having interposed between its ends 20 a pair of brackets of which one is connected to each end of the band, a lever end pivot-

ally fulcrumed in one of said brackets and provided with a socket, a sleeve nut pivoted to the other bracket, a headed rod passing through the nut and pivoted to the lever 35 end of one side of its fulcrum, and a spring interposed between the head of the rod and the nut.

2. A release for the automatic brakes of winding drums comprising a split brake 40 band automatically effective in one direction and having interposed between its ends a pair of brackets of which one is connected to each end of the band, a lever end pivotally fulcrumed in one of said brackets and 45 provided with a socket, a block pivoted in the other bracket, a sleeve nut mounted in the block, a headed rod passing freely through the sleeve nut and pivoted to the lever end to one side of its fulcrum, and a 50 spring interposed between the head of the rod and the sleeve nut.

3. A release for automatic brake bands of winding machines comprising a split brake 55 band automatically effective in one direction, a lever end pivotally fulcrumed to one end of the band, a rod pivoted to the other end of the band and to the lever end at one side of its fulcrum, and a spring and stop 60 carried by the last named end of the band and arranged for cooperation with the rod.

ROBERT H. BEAUMONT.
